US00D940297S

(12) United States Design Patent (10) Patent No.: US D940,297 S
(45) Date of Patent: * Jan. 4, 2022

(54) FEMALE CONDOM

(71) Applicant: VIGAMED PRODUCTS PRIVATE LIMITED, Maharashtra (IN)

(72) Inventor: Viswanathan V. Naidu, Maharashtra (IN)

(73) Assignee: VIGAMED PRODUCTS PVT. LTD., Maharashtra (IN)

() Term: 15 Years

(21) Appl. No.: 29/704,949

(22) Filed: Sep. 9, 2019

(30) Foreign Application Priority Data

Jul. 12, 2019 (IN) 319614-001

(51) LOC (13) Cl. 24-04

(52) U.S. Cl.

USPC D24/105

(58) Field of Classification Search
